LEVER AND LOCK

Robert Thomas and William Thomas,
Philadelphia, Pa.

Application October 21, 1932, Serial No. 638,846

6 Claims. (Cl. 74—531)

This invention relates to levers and locks, and has for an object to provide a lever which may be employed for a variety of purposes, with improved means for locking it relative to a segment.

A further object of the invention is to provide in a device of the class, a segment which is rigidly secured to any approved or convenient body or device, and with a lever pivoted concentrically of the segment having at one end means for the application of manual stress and releasing, and at or adjacent to the opposite end a part movable upon the segment, to which may be applied the working parts, and an improved lock carried by the latter end for locking the lever relative to the segment.

A further object of the invention is to provide in combination with a segment, a lever pivoted concentrically thereof, of a block slideable with the lever upon the segment, and providing means for biting and engaging one of the edges of the segment to maintain the attained position of the lever, and with manual means for releasing the biting engagement of the locking block.

The invention, therefore, comprises a segment which is secured to any permanent supporting means, and has pivoted concentrically thereof a lever to one end of which the power consuming mechanism is applied and at the opposite end means for applying operating stress, said lever carrying a block sliding upon the segment, so constructed that in one position it locks and bites one edge of the segment, and in another position, operates freely upon the segment, the lever carrying at one end means for the application of operating stress, also means for moving the locking block to such disengaged position.

In the drawing:

Figure 1 is a view of an illustrative embodiment of the invention seen in side elevation,

Figure 2 is a view of the lever and other means seen in edge elevation, as indicated by arrow 2 at Figure 1, showing also arrow 1 as the point of view of Figure 1, and

Figure 3 is a fragmentary detail view in elevation of a modification.

The improved lever and lock which forms the subject-matter of this application is adapted, with slight variation, to a very wide range of utilities. As at present contemplated, its greatest field of utility will be that of a hand brake on an automotive vehicle to which it is particularly adapted, but in no way limited.

The illustration as shown in the drawing has been directed largely to the particular type

which would be applicable to such braking purposes, and for that purpose a floor board 10 is shown through which the lever extends. The upper end of the lever at 11 will, of course, be in proper position to be engaged by the hand 5 of the operator.

Beneath the floor a segment 12 is mounted in any approved manner, as by brackets 13. The segment 12 has means for furnishing a central bearing. As shown in the drawing, this means 10 comprises the arms or braces 14, and a pivot 15 is accommodated by such braces.

The lever 11 is pivoted at this pivot point 15 and extends below the pivot point. As shown at Figure 1 the lever is curved, as at 16, 17, and 15 the like, but it is to be understood that this curvature is merely one of example, and that the invention contemplates the use of either a straight lever or other curvatures, as the conditions of installation may make necessary or 20 desirable.

The lever is slotted at 18 to accommodate the segment 12 sliding therethrough, and also a link 19, which is pivoted at 20 to the lever. This link 19 has a block 21 pivoted at 22 to the end 25 opposite the pivot 20. This block 21 is also slotted, as at 23, to move slidably upon the segment 12 when the relation is such that it may so freely slide.

It is, however, provided with a corner 24, as 30 shown at Figure 1, or a slightly rounded shoulder 24', as shown at Figure 3, which, when the block 21 is in the position shown at Figures 1 or 3, will biting engage the inner edge of the segment 12 and lock the lever against movement in 35 the direction indicated by the arrow at the rod 25, which, in the particular embodiment, would be the rod extending to the brake.

The stress of the brake would, therefore, be 40 in the direction indicated by that arrow, and the biting of the corner 24 or shoulder 24' with the segment 12 would prevent such movement.

To effect the biting by the corner 24 or shoulder 24', a spring 26 is provided. This spring is here shown as a helical spring, but it is to be 45 understood that any spring or other resilient means is within the scope of the invention.

The block 21 is provided with an offset 27 to which is applied the stress for releasing the block. This may be applied by any type of 50 mechanical means found applicable to the particular installation.

There is shown in the drawing a rod 28 which is extended upwardly alongside the lever 11 and connected with the thumb piece 29, which is 55

pivoted at 30. When the thumb piece 29 is swung to dotted line position, it depresses the rod 28 and moves the block 21 against the tension of the spring 26, also to dotted line position.

5 In the particular example shown, the rod 28 is provided with an out curve 31 passing about the segment 12, but it is to be understood, of course, that this will follow other changes or modifications of the organization.

10 In use, stress will be applied to the upper end of the lever 11 in the direction indicated by the arrow, which will, through the fulcrum 15, apply stress to the rod 25 or such mechanical devices as may be attached to that end of the lever.

15 The entire device will move along the segment 12 by a sliding action, and absolutely without noise, until the proper tension has been applied. At that attained position, the lever will be held by the biting engagement of the corner 24 or 20 shoulder 24' with the segment, which is transmitted to the lever through the link 19.

25 The position and angle of the link 19 is such that the greater the stress upon the lever 11 the greater the biting effect of the corner 24 or shoulder 24' upon the segment so that it will be impossible to release the engagement without action taken to that end.

30 This action is manually accomplished by swinging the thumb piece 29 to dotted line position, which will change the angular positioning of the block 21 so that the upper edge of the recess 23, which terminates at one side in the biting edge 24 or adjacent thereto in the shoulder 24', will lie substantially parallel with the 35 lines of the segment 12 and will, therefore, move along the segment without engagement.

35 The seating of the brake, if such be the instrumentality, and releasing the same, is accomplished with absolute noiselessness and the device is such that it will hold at any attained 40 position, not depending upon the spacing of notches of a rack, as is customary in such devices.

45 The particular advantages are, therefore, the absolute retention of the attained tension, the noiseless moving of the device in both directions, and the maintaining of the attained position at any point, irrespective of any spacing of parts.

50 Of course, the lever and lock illustrated may be modified and changed in various ways without departing from the invention herein set forth and hereafter claimed.

We claim:—

55 1. The combination of a segment, a lever fulcrumed concentrically of the segment and extending from the segment beyond the fulcrum and provided at said extended end with a hand hold, a block slidably upon the segment and having means for making biting engagement there- 60 with, and a link connecting the block and lever.

2. The combination with a dependent segment, of a lever fulcrumed concentrically thereof and

extending thereabove and to said segment, a block having a recess proportioned to slide upon the segment, and contoured to provide a biting part, and a link connecting said block and extended end of the lever.

5 3. The combination with a segment, of a lever fulcrumed concentrically thereof and having one end extending toward the segment and the other end extending in the opposite direction, a block having a recess mounted to slide upon the segment adjacent to the end of the lever extending in that direction, said recess being contoured to provide a part having biting engagement with the edge of the segment, a link connecting the block and lever, and mechanical means for releasing the biting engagement of the block with the segment.

10 4. The combination with a segment, of a lever fulcrumed intermediate its ends concentrically of the segment and extending upon opposite sides of the fulcrum, one of said extensions being in the direction of the segment, a block provided with a slot sliding upon the segment, said slot being contoured to provide a part adapted to make biting engagement with the segment, a 15 link connecting the lever and block, said link having an inclination toward the fulcrum, a resilient member tending to hold the block in biting engagement with the segment, and manual means to apply stress in opposition to said 20 resilient means to disengage the biting engagement.

25 5. The combination with a segment, of a lever fulcrumed intermediate its ends concentrically of the segment and extending in opposite 30 directions from the fulcrum, one of said extensions being toward the segment, an L-shaped block having a recess therethrough mounted to slide upon this segment, said recess being contoured to provide a part adapted to make biting 35 engagement with the segment, a link connecting the block and lever, said link normally occupying an inclination toward the fulcrum, a resilient member tending to hold the block in biting engagement with the segment, and means to apply 40 manual stress to one leg of the block to move the block against the tension of the resilient member and release the biting engagement.

45 6. In combination a lever having a slot therethrough, a block having a slot therethrough, a segment slidably positioned through both slots, the walls of the slot through the block being contoured to make biting engagement with the segment, a link pivoted in the slot of the lever and inclined to and connecting the lever and 50 block, work applying means carried by the lever, and manual means to oscillate the link to release the block from engagement with the segment.

55 ROBERT THOMAS. 60
WILLIAM THOMAS.
